GOLF GAME DEVICE

John J. Shelley, Jr., Kansas City, Mo.

Application December 21, 1938, Serial No. 247,018

6 Claims. (Cl. 273—32)

This invention relates to a golf game apparatus wherein ball receiving pockets are positioned at predetermined, spaced apart distances from the tee.

5 The principal object of this invention is the provision of a ball receiving pocket of substantially inverted conical shape, having a central, lower opening through which the golf balls pass to enter a container supported therebeneath.

10 A further object of the present invention is the provision of a golf ball receiving pocket comprising an annular ring, supported on standards above the ground surface, an inverted, conical member, made of pliable material and releasably secured to said ring, whereby an inwardly and downwardly inclined wall is formed, said conical member terminating within an annular ring to present a bottom opening through which golf balls delivered to the frusto-conical member, will 15 pass to a golf ball container positioned therebelow.

With these and other objects which will appear during the course of the specification, in view, reference will now be had to the drawing where- 20 in:

Figure 1 is a diagrammatic view of a golf game including several similar golf game devices embodying this invention.

Fig. 2 is an enlarged vertical central section 25 of one of the golf game devices.

Fig. 3 is an enlarged detailed central section of the central portion of the device.

Fig. 4 is a horizontal section taken on line IV—IV of Fig. 3 with parts broken away.

30 Fig. 5 is an enlarged central section of the outside ring and associated parts; and,

Fig. 6 is an enlarged central section of the ring at its connection with one of the supporting standards.

40 This game consists of a series of devices 10 spaced at predetermined distances on a driving course, as indicated in Fig. 1. The contestant drives the golf ball from one of the tees 12 in an endeavor to cause it to be deposited in one 45 of the devices 10, as hereinafter set forth.

Sand traps 14, or any other desirable hazards, may be provided in order to produce conditions somewhat similar to those encountered in the regular golf course.

50 The golf game device 10 constitutes the salient part of this invention and consists of a ring 16 which is shown to be of an annular shape. The contour of this ring might be varied without departing from the spirit of the invention.

55 Detachably secured to ring 16 is a pliable

frusto-conical member 18, preferably made of a heavy fabricated material which will not cause the projected golf balls to rebound. This member 18 may be foraminous or provided with eyelets 20 in order to preclude the accumulation of 5 excessive water during rain storms.

The outer edge portion 22 of member 18 is folded over ring 16 and secured by means of a glove fastener 24 to the main body of member 18, as clearly shown in Fig. 5. This frusto-conical member 18, when so positioned, presents an inwardly and downwardly extending wall 26 of sufficient inclination to cause the golf ball to roll to the lower central opening 28. This central opening 28 is slightly larger than the diameter of a golf ball and is maintained at a fixed dimension by means of an annular metal ring 30 provided with an inner bead 32 on which is mounted a cushion member 34. This cushion member serves as a bearing for the edge portion 10 of the fabricated material of member 18 and also precludes the possibility of the golf ball striking a rigid metallic part which might cause it to rebound or injure the fabric material. 15

A depending tubular member 36 having an annular flange 38 is secured to ring 30 by means of bolts 40 with the edge portion 42 of the fabricated material therebetween. When bolts 40 are securely tightened, they will hold the associated parts in a definite fixed relation. 20

30 Tubular member 36 is provided with oppositely disposed bayonet slots 44 which are adapted to receive pins 46 carried on the inner wall of the neck 48 of ball container 50. This ball container is made sufficiently large to receive a suitable number of the golf balls as they are deposited 35 in the frusto-conical member.

35 In order to prevent accidental rolling of the golf ball from member 18, a tuck or plait 52 is provided. This tuck is produced by folding together and stitching as at 54, the cloth adjacent the outer edge of the frusto-conical member. This tuck extends entirely around the frusto-conical member and is preferably positioned just inside the line of glove fasteners, as indicated in 40 Fig. 5.

45 It is necessary to support the assembly just described above the surface of the ground with the plane of ring 16 substantially parallel therewith. This is accomplished by providing standards 56 which are adapted to be driven into the ground with their end portions extending thereabove to receive ring 16. 50

55 Referring to Fig. 6, it will be noted that a horizontally disposed U-shaped yoke 58 is pro-

vided at the top of standard 56. The yoke and standard are preferably welded together with the yoke extending therebeyond and perforated at 60 to receive a pin 62 which serves to hold the standard and ring in fixed relation.

It will be noted that the fabric is cut away at 64 in order to permit the positioning of ring in yoke 58.

Should it be found desirable to slightly incline the plane of ring 16, relative to the ground surface this can be accomplished by simply driving the front or rear standard a greater depth into the ground.

In the playing of this game, each contestant will be provided with balls bearing like numerals so that at the end of the game, the attendant removes the balls from the various devices 10 and credits the contestant with the number of balls he has deposited in said devices.

With this type of equipment, wherein the container 50 is sufficiently large, it is apparent that the attendant would be able to keep proper records of this game with a minimum amount of labor. Furthermore, these records would be accurate.

It will be noted that the diameters of the various devices 10 vary to suit the distances of the drives.

Having thus described the invention, what is claimed as new and desired to be secured by Letters Patent is:

1. A golf game apparatus comprising a ring supported in substantially horizontal position above a supporting surface; a pliable member detachably supported and presenting a downwardly extending wall terminating in a central opening; a depending flange member circumscribing said central opening; and a ball container removably secured to said flange member adapted to receive the golf balls received on said pliable member and delivered through said central opening.

2. A golf game apparatus comprising a ring supported in substantially horizontal position above a supporting surface; a pliable member detachably supported at its marginal edge to said ring and presenting an inwardly and downwardly extending wall terminating in a central opening; an upwardly extending tuck formed in the marginal edge portion of said pliable member within the confines of said ring; and a ball container carried by said pliable member beneath said central opening whereby balls deposited on

said pliable member will be directed through said central opening and into said container.

3. A golf game apparatus comprising a ring supported in substantially horizontal position above a supporting surface; a pliable, foraminous member detachably supported at its marginal edges to said ring and presenting an inwardly and downwardly extending wall terminating in a central opening; a depending flange member circumscribing said central opening; and a ball container removably secured to said flange member adapted to receive the golf balls received on said pliable member and delivered through said central opening.

4. A golf game apparatus comprising a ring supported in substantially horizontal position above a supporting surface by spaced apart, detachable standards; a pliable member detachably supported at its marginal edge to said ring and presenting an inwardly and downwardly extending wall terminating in a central opening; an upwardly extending tuck formed in the marginal edge portion of said pliable member within the confines of said ring; and a ball container detachably carried by said pliable member beneath said central opening, whereby balls deposited on said pliable member will be directed through said central opening and into said container.

5. A golf game apparatus comprising an annular ring detachably supported in a substantially horizontal position on vertically disposed standards; a substantially frusto-conical pliable member detachably secured at its outer marginal edge to said ring; a flanged ring secured at the central portion of said conical member whereby an opening is provided at the lowest point of said conical member; and an annular cushion member positioned intermediate said conical member and said flanged ring.

6. A golf game apparatus comprising an inverted, frusto-conical member having pliable walls and a lower central opening whereby golf balls delivered to the frusto-conical member will be directed through said central opening; an inwardly and upwardly extending, continuous plait formed adjacent the marginal edge of said frusto-conical member and disposed at substantially right angles thereto; and a golf ball container removably carried by said frusto-conical member to receive balls passing through said central opening.
